UNITED STATES PATENT OFFICE.

JAMES H. RAND, JR., OF TONAWANDA, NEW YORK, ASSIGNOR TO AMERICAN KARDEX COMPANY, OF TONAWANDA, NEW YORK.

DESIGN FOR A CABINET UNIT.

60,998.

Specification for Design.

Patented May 23, 1922.

Application filed May 27, 1920. Serial No. 384,740. Term of patent 14 years.

To all whom it may concern:

Be it known that I, JAMES H. RAND, Jr., a citizen of the United States, residing at Tonawanda, in the county of Erie and State of New York, have invented a new, original, and ornamental Design for a Cabinet Unit, of which the following is a specification, reference being had to the accompanying drawing, forming a part thereof.

The accompanying drawing is a perspective view of a cabinet unit embodying the design.

I claim—

The ornamental design for a cabinet unit, substantially as shown.

JAMES H. RAND, JR.
